JOHN L. DINSMOOR, OF BROOKLYN, NEW YORK, ASSIGNOR TO WESTINGHOUSE ELECTRIC AND MANUFACTURING COMPANY, A CORPORATION OF PENNSYLVANIA.

ARC-LAMP.

1,238,277.

Specification of Letters Patent. Patented Aug. 28, 1917.

Application filed April 24, 1913. Serial No. 763,283.

To all whom it may concern:

Be it known that I, JOHN L. DINSMOOR, a citizen of the United States, and a resident of Brooklyn, in the county of Kings and State of New York, have invented a new and useful Improvement in Arc-Lamps, of which the following is a specification.

My invention relates to electric arc lamps, and it has particular reference to means for substantially eliminating or neutralizing the disturbing magnetic fields in the vicinity of the arcs.

Because an electric arc is a gaseous conductor of electric current, it possesses qualities that detract from its stability and cause a flickering of the light emitted therefrom. Some of the disturbing factors upon arc stability are heat radiation, expansion and diffusion of the gaseous medium of the arc, forces resulting from air currents, and magnetic fields existing in the vicinity of the arc. In modern types of arc lamps, the magnetic fields existing in the vicinity of the arc are the disturbing factors which most affect its stability. Inasmuch as an unsymmetrical magnetic field produces perceptible changes in the shape and position of the arc, it is important that the disturbing forces resulting from such a magnetic field be minimized to a substantially low value.

An arc burning under the influence of adjacent and unsymmetrically disposed magnetic fields will be distorted and eventually will crawl up the sides of the upper electrode and cause uneven burning of the arcing end of the electrode. This results in a further distortion of the shape of the normal arc followed by an actual change in its position and ultimately in an elongation which terminates often in the rupture of the arc.

One object of my invention is to provide means, in an electric arc lamp, for substantially eliminating or minimizing the disturbing magnetic forces which may arise from the magnetic fields adjacent to the arc.

Another object of my invention is to provide means in an electric arc lamp, for insuring stability of the arc and thereby preventing material flickering of the light which is emitted from the arc.

A further object of my invention is to provide means, in an electric arc lamp, that will cause the surfaces of the opposing ends

of the electrodes to burn evenly during the consumption of the electrodes.

For a better understanding of the nature of my invention, reference may be had to the following description and the accompanying drawing in which Figure 1 is a side view, partially in section, of a portion of an arc lamp equipped with a device embodying one form of my invention; Fig. 2 is a front view of my device, showing its position relative to the operating position of the electrodes of the lamp, and Fig. 3 is a front view of my device.

Referring to the drawings, the arc 1 between the opposing ends of an upper electrode 2 and a lower electrode 3, is inclosed by a globe (not shown) which excludes all air currents from the immediate vicinity of the arc. The electric current of the arc 1 is conducted by a supporting rod 4 which passes slidably through a sleeve 5, a holder 6, the lower electrode 3 and the upper electrode 2. As the current flows along the rod 4 and through the other conductors embodied in the lamp, it generates a magnetic field unsymmetrically disposed around the arc 1 which unbalances the arc and decreases its stability. A device 7, shown in Fig. 3 and constructed in accordance with my invention, is placed upon the tapered sleeve 5 in the position shown in the drawings. The device 7 which constitutes a magnet having a north pole and a south pole is made of paramagnetic material, preferably sheet steel of high permeability. Its shape conforms substantially to that of a strip of material of definite width being wound upon a section of a helix and provided with a slot 8 which extends parallel to the direction of the axis of the helix. As a result, the device 7 may be considered as made of a strip of metal at the ends of which magnetic poles may be formed when subjected to a magnetizing force. When current flows along the rod 4, this magnetizing force is generated thereby forming a pair of poles at the opposing ends of the strip of metal which are spaced from each other by the slot 8.

Referring to Figs. 1 and 2, the magnet 7 is shown positioned upon the sleeve 5 with the slot 8 adjacent to the side of the sleeve 5 which is the more remote from the arc 1. In

order to secure very beneficial results upon the arc resulting from the magnet 7, the slot 8 should be disposed opposite to the space extending between the opposing ends 5 of the electrodes 2 and 3 when in their operating position. By reason of the magnetic field generated by the magnet 7 which is of such a character as to neutralize other disturbing fields occasioned by the current flow 10 through the conductors embodied in the lamp, the disturbing magnetic forces which impair the arc's stability are substantially neutralized. While it is very difficult to determine the magnetic fields which disturb 15 the arc in an arc lamp, I have found, from extensive experiments, that a device having the form shown in Fig. 3 is very effective in stabilizing the arc. Consequently, it may be inferred that a magnet of the character 20 shown and described and having poles formed at 9 and 10 (Fig. 3) greatly minimizes the magnetic disturbing forces impressed upon the arc 1. I am aware that electromagnets having exciting windings 25 connected to the supply circuits of arc lamps are old in the art, and it is well known that magnetic shields have been provided in arc lamps to preclude leakage fluxes from disturbing the arcs, but, I believe, that I am the 30 first to propose magnets of the character disclosed in this specification for stabilizing the arcs in arc lamps.

While I have shown, and described one embodiment of my invention, it is evident 35 that many modifications and changes may be made without departing from the spirit thereof, and I do not wish, therefore, to limit myself to the precise disclosure herein set forth.

40 I claim as my invention:

1. An electric arc lamp comprising aligned electrodes adapted to maintain an arc between their adjacent and opposing ends, a conductor for electric current disposed parallel and adjacent to said electrodes, and a sleeve embracing said conductor and dis-

posed opposite to the arc, said sleeve made of paramagnetic material and provided with a longitudinal slot.

2. An electric arc lamp comprising electrodes adapted to maintain an arc between their arcing ends, a conductor for electric current disposed adjacent to said electrodes, and an arc-stabilizing member of paramagnetic material substantially surrounding 55 said conductor adjacent to the arc.

3. An electric arc lamp comprising electrodes adapted to maintain an arc between their arcing ends, a conductor for electric current disposed adjacent to said electrodes, 60 and a helical shaped sleeve embracing said conductor and disposed opposite to the arc, said sleeve being made of magnetizable material.

4. An electric arc lamp comprising electrodes adapted to maintain an arc between their arcing ends, a conductor for electric current disposed adjacent to said electrodes, and a sleeve embracing said conductor, said sleeve being made of paramagnetic material 70 and provided with a longitudinal slot for forming a pair of magnetic poles when the sleeve is subjected to a magnetizing force.

5. An electric arc lamp comprising electrodes adapted to maintain an arc between 75 their arcing ends, a conductor for electric current disposed adjacent to said electrodes, and a sleeve embracing said conductor and disposed opposite to the arc, said sleeve being made of paramagnetic material and 80 provided with a longitudinal slot by means of which a pair of magnetic poles may be formed on the sleeve when the same is subjected to a magnetizing force.

In testimony whereof, I have hereunto 85 subscribed my name this 5th day of April 1913.

JOHN L. DINSMOOR.
